BOTTLE

Andre Courreges, Neuilly, France, assignor to Courreges Parfums, Paris, France

Filed Jan. 23, 1970, Ser. No. 21,054

Term of patent 14 years

Int. Cl. D9—01

U.S. Cl. D9—145

FIG. 1 is a perspective view from above of a bottle showing my new design;

FIG. 2 is a top plan view thereof; and

FIG. 3 is a side elevational view thereof.

The stippling in the drawing shows opaque surfaces.
I claim:

The ornamental design for a bottle, as shown and described.
